UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKE-OVEN SMOKE-DISCHARGING MEANS.

1,376,314.

Specification of Letters Patent. Patented Apr. 26, 1921.

Application filed October 16, 1919. Serial No. 330,990.

To all whom it may concern:

Be it known that I, JOSEPH BECKER, a citizen of the United States, residing in Pittsburgh, in the county of Allegheny and State of Pennsylvania, have invented a new and useful Improvement in Coke-Oven Smoke-Discharging Means, of which the following is a specification.

This invention relates in general to coking plants and has for its essential object the provision of an efficient means for taking care of the smoke incidental to the charging of a heated coking oven, which permits the smoke offtake to continue until the leveling operation has been effected, thereby insuring proper discharge of smoke from a coke oven during the entire period of charging and preparing the charge within the oven for coking, with the result that trapping of smoke within the oven is eliminated.

A further highly important object of the invention is the provision of means for discharging the smoke either into a smoke main or into the usual gas collecting main, so that, if desired, the valuable by-products carried along with the gas laden smoke may be recovered with the gas evolved in the coking of the charges within the several chambers of the plant and discharged into said gas collecting main.

With the above and other objects in view, the invention consists in certain novel arrangements, construction and combinations of parts hereinafter described in a preferred form and particularly pointed out in the claims at the end of the specification.

In the drawings:

Figure 1 is a vertical section through the top of a coking chamber of an oven plant, or battery, and showing a charging truck or lorry car in elevation;

Fig. 2 is a top plan view of the truck illustrated in Fig. 1;

Fig. 3 is a side elevation of the truck;

Fig. 4 is an enlarged detailed view of the means employed for coupling the smoke pipe with the smoke main, as will be more fully described hereinafter.

In its present embodiment, the invention is employed in connection with a battery of coking ovens of the by-product type and for

convenience the present description will be confined to this use of the invention; features of construction are however readily susceptible of other valuable applications and consequently it is manifest that the scope of the invention is by no means confined to the specific use and the specific embodiment herein described.

By referring to the drawings, there is indicated at 11 a fragmentary section taken longitudinally through an oven or coking chamber of a coke oven battery, or plant, of the by-product type. It will be understood that the coke oven battery may be of the usual construction, embodying generally a plurality of coking chambers arranged side by side and extending transversely of the battery and provided with the usual alternating heating walls having plane flues intermediate adjacent coking chambers. Each coking chamber or oven is provided with a set of charging holes 12 and also, in the present instance, with a set of smoke outlets 13, the several smoke outlets being each independent of the charging holes. The several charging holes 12 of each oven chamber are arranged at intervals therealong, as clearly shown in Fig. 1, and the independent smoke outlets 13 are disposed in alternation with the charging holes. According to this arrangement, a smoke outlet is located between each pair of adjacent charging holes, with the result that smoke may escape from the oven chamber during charging and until the leveling operation has been completed, through outlets which are intermediate the several mounds of coal deposited in the oven by the charging apparatus, thereby eliminating trapping of smoke in the oven and insuring complete off-take of the smoke, during the charging and leveling interval. The charging holes 12 and the smoke outlets 13 respectively extend through the top 14 of the coking chamber or oven and may each be provided with suitable closures, not shown, but of a construction well known in the art, for closing the top of the oven during the coking operation. It will be understood that the closures of the several charging holes and smoke outlets are removed during the charging operation. At one side of the

coke oven battery, preferably the pusher side, there is provided a collecting main 15, the latter communicating with ascension pipes 16 extending upwardly from gas outlets 17 formed in the top 14 of the respective ovens or chambers 11. The gases evolved from the coking of the charge of coal in each oven or chamber pass upwardly through the ascension pipe and thence into the collecting main 15, through which such gases pass to the by-product recovery apparatus.

The charging of the individual coking chambers or ovens of a coke oven battery is, in the present instance, effected by means of a lorry car adapted to run on tracks 17 extending lengthwise across the top of the battery or series of ovens, whereby the lorry car may be moved into charging position with respect to any of the chambers or ovens to be charged. In its construction, the lorry car embodies a suitable supporting framework for the several instrumentalities mounted on the car, the entire frame and other mechanism being supported upon wheels 18 journaled in suitable bearings 19 supported by the bottom of the frame. The lorry car or truck, in the present instance, is provided with four coal hoppers 19 of general funnel shape and supported by the framework in any suitable manner. The bottoms of the hoppers are located at spaced intervals and are adapted to be positioned directly over the four charging holes 12, as shown more particularly in Fig. 1. Each hopper is normally closed at its bottom by a slide 20 beneath which is located a depending chute 21 provided with an encircling extensible sleeve 22 adapted to be projected into registry with an appropriate charging hole 12 of a coking chamber or oven 11. Whenever a slide 20 is moved from closed position, the charge within the corresponding hopper is emptied through the chute 21 into a coking chamber 11. In order that the hoppers 19 of the lorry car may be opened severally, an individual control is provided for the several slides 20 of the respective hoppers. This individual control includes an operating lever 23 for each slide 20 and independently-operable gearing connections, indicated diagrammatically at 24 in Fig. 2, between the several operating levers 23 and their corresponding slides 20. If desired the levers 23, as well as the other control parts of the lorry car, may be grouped within the cab 25, in which the attendant in control of the car stands. The controlling lever 26 for the extension sleeves 22 of the several chutes 21 is also mounted in the cab 25; the motion of said lever is transmitted by means of appropriate gearing connections 27 between said lever and the several extension sleeves 22 for the purpose of elevating or lowering said sleeves

in unison, it being understood that the operation of all the sleeves 22 is dependent upon the operation of the single sleeve-controlling lever 26.

In addition to the gas collecting main 15, a smoke main 28 is mounted on suitable supports 29 along the side of the battery opposite to the collecting main 15. Preferably this smoke main extends clear along the battery of ovens and is provided with an inlet 30 opposite each coking chamber or oven 11. The construction of the several inlets 30 is designed to close these inlets automatically, when not in use for permitting smoke to enter the main 28, and will be explained hereinafter.

Mounted on the lorry car or truck, and preferably extending laterally thereacross is a smoke pipe or flue 31 which may, if desired, be provided with explosion caps 32 respectively located at the opposite ends of said pipe 31. These explosion caps are conveniently constructed of hinged doors adapted normally to close the opposite ends of the smoke pipe but which readily open upon the accumulation of an undue pressure within said pipe.

In accordance with the present invention means is provided for permitting the smoke evolved from a coke oven or chamber during the charging operation to pass through the smoke outlets 13 in the top of an oven directly into the smoke pipe 31; for this purpose there is provided a plurality of depending smoke-inlet branch pipes or ducts 33 corresponding in number with the several smoke outlets of a coking chamber or oven and leading downwardly from the smoke pipe or flue 31. The ducts or pipes 33 are disposed in alternation with respect to the charging devices or coal hoppers, as shown in Fig. 1, to coöperate with the alternate smoke outlets 13 of an oven chamber and to permit the smoke which collects between the mounds of coal in the oven chamber to pass freely to the smoke pipe 31, from which it can be discharged optionally into the smoke main 28 or the collecting main 15. At their lower end the several branch pipes 33 are provided with encircling sleeves or extensible parts 34 which are adapted to be lowered in unison into smoke conveying position with respect to the corresponding smoke outlets 13 of a coking chamber or oven whenever said sleeves 34 are in registry with smoke outlets. For this purpose each sleeve 34 is pivotally connected by means of vertical links 35, see Fig. 3, with arms 36 fixed on a rock shaft 37, the latter journaled in suitable bearings 38 supported by the frame of the lorry car. Also, fixed on the shaft 37 is a crank arm 39 pivotally connected at its upper end to a link 40, the latter in turn being pivotally connected at its opposite end to an operating lever 41.

preferably located within the cab 25. With this construction the operation of the lever 41 will rock the shaft 37 and through the connections 36, 35 effect a lowering or elevating movement of the several sleeves 34 in unison. If desired the several sleeves 34 may be retained normally in elevated position by means of arms 42 also fixed on the shaft 37 but projecting oppositely from the 10 arms 36 and provided adjacent their outer extremities with counter weights 43.

The smoke discharged through the smoke outlets 13 of a coking chamber or oven 11 into the smoke pipe or flue 31 of the lorry car may, in accordance with the invention, be discharged either into the smoke main 28 or the collecting main 15, or into both of said mains simultaneously as desired. When smoke is discharged into the collecting main 15, the latter not only functions as a smoke main for permitting off-take of the smoke, but also permits the smoke to pass, before its final discharge, through the usual by-product recovery apparatus, where recovery may be had of valuable by-products carried off with the smoke. In order to accomplish this highly desirable control of the discharge of the smoke, the smoke pipe or flue 31 is provided preferably at 25 its opposite ends with coupling elements respectively adapted to connect the collecting main and the smoke main with said smoke pipe independently of each other. At its end adjacent the smoke main, the smoke 30 pipe 31 is provided with a branch pipe 44 extending therefrom in a horizontal plane and provided with an outlet 45 surrounded by a seat 46. Pivoted mounted at 47 on the seat 46 is a coupling member or pipe union 48 having a vertical passageway 49 adapted to communicate with the said outlet 45 and a horizontal passageway 50 adapted to communicate with one of the inlets 30 of the smoke main. Each outlet 30 of the 35 smoke main consists essentially of a short pipe section 51 projecting within and without said main and provided with an inclined inner edge 52 against which a pivoted closure 53 is adapted normally to gravitate into position for closing the outlet of the smoke main. The closure 53 is pivoted at its upper end, as shown at 54, within the smoke main and is shifted from its normally closed position, indicated by dotted 40 lines in Fig. 4, into an open position, indicated by full lines in said figure, by means of the following mechanism. Pivoted at its upper end, as shown at 55, beyond the outer edge 56 of the pipe section 51 is a ring 57 provided with an inwardly projecting cam 58 adapted to engage the closure 53 and shift the latter into open position on movement of the ring 57 toward the outer edge 56 of the pipe section 51. Normally the ring 57 will gravitate away from

the edge 56, into the position shown in dotted lines in Fig. 4, thereby permitting the closure 53 to gravitate into the closed position hereinbefore described. The opening movement of the ring 57 is accomplished by 70 the vertical edge 59 of the coupling member 48, which when the latter is lowered into coupled position with the smoke main, as indicated in full lines in Fig. 4, will engage said ring to shift the same inwardly and 75 open the closure 53. Thus a positive and automatically operating means is provided for preventing escape of smoke through any of the outlets 30, when the latter are not in use. 80

The coupling member 48 is pivoted to the end of a link 60 extending to and pivoted at its opposite end to an operating lever 61, preferably located within the cab 25. If desired a crank arm 62 may be pivoted 85 at 63 on the link 60. The crank arm 62 is pivoted at its opposite end at 64 and is provided with a counterweighted arm 65 for shifting the link 60 to normally throw the coupling member 48 into its inclined or 90 inoperative position, as indicated by dotted lines in Figs. 1 and 4. This construction insures movement of the coupling member into an inoperative position when the smoke discharging operation has been completed 95 51, during the movement of the lorry car on its track.

At its opposite end the smoke pipe 31 is provided with a coupling member adapted 100 to make connection with the collecting main 15 in the event it is desired to discharge the smoke from the pipe 31 into said collecting main. The pipe 31 is provided with a short branch 66 on the outer end of which is pivoted the horizontal portion 67 of a discharge pipe 68. Said pipe 68 is further provided with a vertical portion 69 the outer end of which is turned down, as at 70, so that it may make proper connection with 105 an inlet 71 of the ascension pipe 16 of an oven. The inlet 71 of such ascension pipe may be normally closed by a pivoted cover 72. When it is desired to direct the smoke from the pipe 31 into the collecting main, 110 the cover 72 of an ascension pipe adjacent which the lorry car is stationed, is opened and the pipe 68 is swung into position in which the turndown portion 70 covers the inlet 71 of the ascension pipe. This operation of the pipe permits the smoke to pass 115 into the collecting main and any by-products contained in the smoke will be recovered along with the gases discharged into said main from the other ovens for the battery. 120

Suitable valves, 73, 74, are provided for shutting off the coupling member 48 or the pipe 68 from the smoke pipe 31 whenever said member 48 or pipe 68 is not in use. 130

Obviously it is not intended to permit the smoke to discharge from the pipe 31 directly into the atmosphere.

As the smoke outlets from the coking chamber or oven are independent of the charging holes, and as the smoke discharging mechanism carried by the lorry car is likewise independent of a mechanism for introducing a charge into the oven, the period of smoke offtake may continue after the charging operation has been completed and the covers have been replaced on the charging holes of the oven. In the normal operation of a by-product coke oven large quantities of smoke are evolved until the charge introduced into the coke oven has been leveled. This smoke may, by the use of the smoke discharging means of the present invention, be freely discharged and as a result trapping of smoke evolved from the charge, after the charging operation has been completed, is eliminated; the several smoke outlets, because of their alternate arrangement with respect to the charging holes, communicate with the valleys between the heaps of coal charged into the cooking retort, as shown in Fig. 1, and thus permit free and intermediately direct discharge of the smoke before as well as during the leveling operation. As a result of the provision for conveniently discharging the smoke into the gas collecting main, the valuable by-products contained in the smoke may be readily recovered and there will consequently be practically no waste of by-products.

The invention as hereinabove set forth is embodied in a particular form of construction but may be variously embodied within the scope of the claims hereinafter made.

I claim:

1. In a coke-oven battery, in combination: an elongated oven chamber provided with a plurality of charging holes arranged at intervals along said oven chamber and with independent smoke outlets disposed in alternation with said charging holes; a smoke main; a charging truck movable over the top of said battery into charging position over said oven chamber; a plurality of charging devices carried by said truck for respective coöperation with the respective charging holes of the oven chamber; a smoke pipe also carried by said truck and connectible with the smoke main, for conveying thereto the smoke incidental to oven charging; a plurality of extensible smoke ducts leading from said smoke pipe and disposed in alternation with respect to said charging devices, to coöperate with the alternate smoke outlets of the oven chamber; and means for extending the several ducts in unison into connection with said smoke outlets; substantially as specified.

2. In a coke-oven battery, in combination;

an elongated oven chamber provided with a plurality of charging holes arranged at intervals along said oven chamber and with independent smoke outlets disposed in alternation with said charging holes; a smoke main; a charging truck movable over the top of said battery into charging position over said oven chamber; a plurality of charging devices carried by said truck for respective coöperation with the respective charging holes of the oven chamber; a smoke pipe also carried by said truck and connectible with the smoke main, for conveying thereto the smoke incidental to oven charging; a plurality of extensible smoke ducts leading from said smoke pipe and disposed in alternation with respect to said charging devices, to coöperate with the alternate smoke outlets of the oven chamber; and means for extending the several ducts into connection with said smoke outlets; substantially as specified.

3. In a coke-oven battery, in combination: an elongated oven chamber provided with a plurality of charging holes arranged at intervals along said oven chamber and with independent smoke outlets disposed in alternation with said charging holes; a smoke main; a charging truck movable over the top of said battery into charging position over said oven chamber; a plurality of charging devices carried by said truck for respective coöperation with the respective charging holes of the oven chamber; a smoke pipe also carried by said truck and connectible with the smoke main, for conveying thereto the smoke incidental to oven charging; and a plurality of smoke ducts leading from said smoke pipe and disposed in alternation with respect to said charging devices, to connect with the alternate smoke outlets of the oven chamber; substantially as specified.

4. In a coke-oven battery, in combination: an elongated oven chamber provided with a plurality of charging holes arranged at intervals along said oven chamber and with independent smoke outlets disposed in alternation with said charging holes; a smoke main; a charging truck movable over the top of said battery into charging position over said oven chamber; a plurality of charging devices carried by said truck for respective coöperation with the respective charging holes of the oven chamber; a plurality of smoke ducts also carried by said truck and disposed in alternation with respect to said charging devices, to connect with the alternate smoke outlets of the oven chamber for conveying to said smoke main the smoke incidental to oven charging; and means for connecting said ducts with said smoke main; substantially as specified.

5. A charging truck for a coke-oven battery having a smoke main and an elongated oven chamber provided with a plurality of

- charging holes arranged at intervals along said oven chamber and with independent smoke outlets disposed in alternation with said charging holes, said charging truck 5 comprising a plurality of charging devices for respective coöperation with the respective charging holes of the oven chamber, a smoke pipe connectible with said smoke main for conveying thereto smoke incidental 10 to oven charging, a plurality of extensible smoke ducts leading from said smoke pipe and disposed in alternation with respect to said charging devices to coöperate with the alternate smoke outlets of the oven chamber, 15 and means for extending the several ducts in unison into connection with the smoke outlets of an oven chamber, substantially as specified.
6. A charging truck for a coke-oven battery having a smoke main and an elongated oven chamber provided with a plurality of charging holes arranged at intervals along said oven chamber and with independent smoke outlets disposed in alternation with 20 said charging holes, said charging truck comprising a plurality of charging devices for respective coöperation with the respective charging holes of the oven chamber, a smoke pipe connectible with said smoke main for conveying thereto smoke incidental 25 to oven charging, a plurality of extensible smoke ducts leading from said smoke pipe and disposed in alternation with respect to said charging devices to coöperate with the alternate smoke outlets of the oven chamber, and means for extending the several ducts 30 into connection with the smoke outlets of an oven chamber, substantially as specified.
7. A charging truck for a coke-oven battery having a smoke main and an elongated oven chamber provided with a plurality of charging holes arranged at intervals along said oven chamber and with independent smoke outlets disposed in alternation with 35 said charging holes, said charging truck comprising a plurality of charging devices for respective coöperation with the respective charging holes of the oven chamber, a plurality of smoke ducts disposed in alternation with respect to said charging devices, to connect with the alternate smoke outlets of the oven chamber, for conveying to said smoke main the smoke incidental to oven charging, and means for connecting said 40 ducts with said smoke main, substantially as specified.
8. In a coke-oven, in combination: an elongated oven chamber provided with a plurality of charging holes arranged at intervals along said oven chamber, and with independent smoke outlets disposed in alternation with said charging holes and respectively leading directly into the atmosphere; a smoke main; and means, operable at will, 45 for connecting in unison the several smoke outlets of the oven chamber with said smoke main; substantially as specified.
9. In a coke-oven, in combination: an elongated oven chamber provided with a plurality of charging holes arranged at intervals along said oven chamber and with independent smoke outlets disposed in alternation with said charging holes and respectively leading directly into the atmosphere; a smoke main; an oven-charging mechanism; and means carried by said charging mechanism and operable at will 50 for connecting in unison the several smoke outlets of the oven chamber with said smoke main; substantially as specified.
10. In a coke-oven battery, in combination: an elongated oven chamber provided with a plurality of charging holes arranged at intervals along said oven chamber and with independent smoke outlets disposed in alternation with said charging holes; a smoke main; a gas collecting main; a charging truck movable over the top of said battery into charging position over said oven chamber; a plurality of charging devices 55 carried by said truck for respective coöperation with the respective charging holes of the oven chamber; a smoke pipe also carried by said truck; means for selectively connecting said smoke pipe with either or both of said mains, for conveying thereto the smoke incidental to oven charging; and a plurality of smoke ducts leading from said smoke pipe and disposed in alternation with respect to said charging devices to connect with the alternate smoke outlets of the oven chamber; substantially as specified.
11. In a coke-oven battery, in combination: an elongated oven chamber provided with a plurality of charging holes arranged at intervals along said oven chamber and with independent smoke outlets disposed in alternation with said charging holes; a smoke main; a gas collecting main; a charging truck movable over the top of said battery into charging position over said oven chamber; a plurality of charging devices 60 carried by said truck for respective coöperation with the respective charging holes of the oven chamber; a smoke pipe also carried by said truck; means for selectively connecting said smoke pipe with either of said mains for conveying thereto the smoke incidental to oven charging; and a plurality of smoke ducts leading from said smoke pipe and disposed in alternation with respect to said charging devices, to connect with the alternate smoke outlets of the oven chamber; substantially as specified.
12. In a coke-oven, in combination: an elongated oven chamber provided with a plurality of charging holes arranged at intervals along said oven chamber and with independent smoke outlets disposed in alternation with said charging holes and respec-

tively leading directly into the atmosphere; a smoke main; a gas collecting main; and means, operable at will, for selectively connecting in unison the several smoke outlets 5 of the oven chamber with either or both of said mains; substantially as specified.

13. In a coke-oven, in combination: an elongated oven chamber provided with a plurality of charging holes arranged at intervals along said oven chamber and with independent smoke outlets disposed in alternation with said charging holes and respectively leading directly into the atmosphere; a smoke main; a gas collecting main; and 10 means, operable at will, for selectively connecting in unison the several smoke outlets of the oven chamber with either of said mains; substantially as specified.

14. In a coke-oven, in combination: an elongated oven chamber provided with a 15

plurality of smoke outlets respectively leading directly into the atmosphere; a smoke main; a gas collecting main; and means, operable at will, for selectively connecting in unison the several smoke outlets of the oven 25 chamber with either or both of said mains; substantially as specified.

15. In a coke-oven, in combination: an elongated oven chamber provided with a plurality of smoke outlets respectively leading directly into the atmosphere; a smoke main; a gas collecting main; and means, operable at will, for selectively connecting in unison the several smoke outlets of the oven chamber with either of said mains; 30 substantially as specified.

In testimony whereof I have hereunto set my hand this 6th day of October, 1919.

JOSEPH BECKER.
